HETEROCYCLIC AMIDES

Margaret H. Sherlock, Bloomfield, and Nathan Sperber, North Caldwell, N.J., assignors to Schering Corporation, Bloomfield, N.J., a corporation of New Jersey

No Drawing. Application April 29, 1957
Serial No. 655,539

9 Claims. (Cl. 260—243)

This invention relates to a new group of chemical compounds which possess valuable therapeutic properties and to processes for their manufacture. More particularly, our invention relates to isonipecotylphenothiazines and pharmaceutical compositions thereof which are useful in allaying bronchospasm and relieving tremors associated with Parkinson's disease.

The compounds of our invention are represented by the following general formula and include the non-toxic acid addition salts thereof:

wherein X is a member of the group consisting of hydrogen, chlorine, fluorine, bromine, lower alkanoyl, and trifluoromethyl, and R is a lower alkyl group.

We have found that our new compounds possess significant physiological properties useful in the treatment of bronchospasm and Parkinson's disease. Furthermore, the compounds of this invention show remarkable selectivity in blocking pilocarpine-induced bronchospasm without causing undesirable side effects such as mydriasis and xerostenia. Moreover, our compounds, in doses sufficient to block the *in vitro* spasmolytic effects of acetylcholine on the tracheal chain and perfused lung, are equally active in blocking the spasmolytic effects of histamine. Thus, our compounds appear to possess a combination of anticholinergic and antihistaminic activities, which are unique in their specificity for treatment of bronchospasm.

The ability to block pilocarpine-induced bronchospasm appears to be a property of both the isonipecotylphenothiazines of our invention and their 3-isomers, the nipecotylphenothiazines. We have found, however, that our compounds are significantly more potent and have a more favorable therapeutic ratio than their isomers. For example, via intravenous administration in dogs, we have found that 10-(N-methylisonipecotyl)-phenothiazine is 33 times as potent as atropine and 11 times as potent as its 3-isomer, 10-(N-methylnipecotyl)-phenothiazine in relieving bronchospasm. Furthermore, the isonipecotyl derivative has greater specificity of action with minimal side effects. In view of the advantageous therapeutic ratio, the isonipecotyl derivatives are distinct from, and preferred to, their position isomers.

The present treatment of Parkinsonism has been limited by the appearance of undesirable side effects produced by the medicament employed. The unique specificity of the compounds of our invention in overcoming the effects of acetyl-choline in bronchial smooth muscle is accom-

2

panied by a similar specificity of cholinergic blockade within the central nervous system without untoward side effects. These advantageous properties make our compounds more effective than agents currently employed in 5 Parkinsonism and provide for favorable control of symptoms without concomitant side effects.

The compounds of our invention are readily prepared via a conventional amide synthesis. Reacting a phenothiazine or its 2-X substitution products, wherein X is as 10 above defined, with an N-lower alkyl isonipecotyl halide yields the amides of our invention. We prefer to use an acid salt of an isonipecotylchloride such as N-methylisonipecotylchloride hydrochloride and effect the reaction in an inert solvent such as benzene, toluene, xylene and 15 the like. To hasten the reaction we prefer to heat the mixture, generally at reflux.

The acid salts are usually prepared from the free base and a non-toxic acid preferably in an inert solvent such as ether, benzene, ethyl acetate and the like, whereby the 20 salt precipitates in a relatively pure state. Examples of non-toxic salts which may be prepared in this manner are the hydrochloride, phosphate, maleate, citrate, tartrate, salicylate and the like.

The following examples are intended merely to illustrate the invention and are not to be construed as limiting the scope thereof:

EXAMPLE 1

10-(N-methylisonipecotyl)-phenothiazine

30 Phenothiazine (40 g.) is added portionwise to a suspension of N-methylisonipecotylchloride hydrochloride (from 36 g. of N-methylisonipecotic acid hydrochloride) in 800 ml. anhydrous benzene. The reaction mixture is stirred and refluxed for 12 hours, then one liter of water is added. The aqueous layer is separated and the benzene layer extracted several times with dilute hydrochloric acid. The acid extracts combined with the original aqueous layer are basified with dilute sodium hydroxide solution, and a gummy material separates which slowly crystallizes. Several recrystallizations from benzene-petroleum ether yields 10-(N-methylisonipecotyl)-phenothiazine as a yellow solid, M.P. 179-180° C.

The hydrochloride is prepared from the free base with ethanolic hydrogen chloride. The salt is obtained as the monohydrate, and melts at 241-242° C., after several recrystallizations from ethanol-ether.

EXAMPLE 2

10-(N-methylisonipecotyl)-2-chlorophenothiazine

50 2-chlorophenothiazine (10 g.) is added portionwise to a suspension of N-methylisonipecotylchloride hydrochloride (from 10.7 g. of N-methylisonipecotic acid hydrochloride) in 200 ml. of anhydrous benzene. After stirring and refluxing the reaction mixture for 12 hours, the crude product is filtered from the benzene solution and recrystallized from ethanol to yield the hydrochloride salt of 10-(N-methylisonipecotyl)-2-chlorophenothiazine, M.P. 263.5-264.5° C.

60 When the hydrochloride salt so obtained is dissolved in hot water and the resulting solution made basic with sodium hydroxide solution, the free base, 10-(N-methylisonipecotyl)-2-chlorophenothiazine is precipitated, filtered, and recrystallized from ethanol-water, M.P. 65 190-191° C.

EXAMPLE 3

10-(N-methylisonipecotyl)-2-bromophenothiazine

70 2-bromophenothiazine (11 g.) is reacted with a suspension of N-methylisonipecotylchloride hydrochloride (from 10.7 g. of N-methylisonipecotic acid hydrochloride) in 200 ml. anhydrous benzene in the manner de-

scribed in Example 2. The hydrochloric acid salt of 10-(N-methylisonipecotyl)-2-bromophenothiazine which is formed, crystallizes from methanol as colorless crystals. When the hydrochloride salt so obtained is further treated as in Example 2, the free base is isolated as a light tan solid which is crystallized from ethanol-water.

EXAMPLE 4

10-(N-isopropylisonipecotyl)-phenothiazine

The requisite intermediate, methyl N-isopropylisonipecotate, B.P. 127-130° C./3 mm. Hg, is prepared by the alkylation of methyl isonipeotate with potassium carbonate and isopropyl iodide in benzene.

A solution of 17.5 g. of methyl N-isopropylisonipecotate and 100 ml. of concentrated hydrochloric acid is heated on a steam bath for 16 hours, concentrated to dryness, then refluxed for two hours with 50 ml. of thionyl chloride. After the excess thionyl chloride is removed in vacuo, the residual solid is suspended in 400 ml. of anhydrous benzene, and 20 g. of phenothiazine is added portionwise. The reaction mixture is stirred and refluxed for 12 hours. One liter of water is then added, the aqueous layer separated, and the basic layer extracted several times with dilute hydrochloric acid. The acid extracts combined with the original aqueous layer are made basic with dilute sodium hydroxide solution and are then extracted with ether. The ether solution is cooled to -30° C. in an acetone Dry Ice bath and the green solid which precipitates is filtered. Extraction of the solid in a Soxhlet extractor with hexane yields 10-(N-isopropylisonipecotyl)-phenothiazine as a yellow crystalline solid.

This crystalline amide is converted to the maleate salt in ethyl acetate with an equimolar amount of maleic acid in ethyl acetate.

EXAMPLE 5

10-(N-methylisonipecotyl)-2-acetylphenothiazine

2-acetylphenothiazine (10 g.) is reacted with a suspension of N-methylisonipecotylchloride hydrochloride (from 10.7 g. of N-methylisonipecotic acid hydrochloride) in 200 ml. of anhydrous benzene, in the manner described in Example 2, to yield the hydrochloric acid salt of 10-(N-methylisonipecotyl)-2-acetylphenothiazine which is crystallized from methanol. When the hydrochloride salt M.P. 225-226° C. (monohydrate) so obtained is further treated as in Example 2, the free base is isolated as a light tan solid which is crystallized from ethanol-water.

EXAMPLE 6

10-(N-methylisonipecotyl)-2-trifluoromethylphenothiazine

To a stirred solution of 2-trifluoromethylphenothiazine (21 g.) in 200 ml. of dry benzene, there is added crude N-methylisonipecotylchloride hydrochloride (from 18 g. of N-methylisonipecotic acid hydrochloride). The reaction mixture is stirred and refluxed for 18 hours, then 500 ml. of water is added. The aqueous layer is separated and made basic with sodium hydroxide. The oil which separates is extracted with benzene, and these extracts, in turn, are concentrated in vacuo to an oily residue. This residue is dissolved in 200 ml. of hexane treated with charcoal, filtered and cooled. The product of our invention, 10-(N-methylisonipecotyl)-2-trifluoromethylphenothiazine, precipitates as a tan solid (3.12 g.), M.P. 136-137.5° C.

The hydrochloride salt of the above compound is prepared by adding an ethanol solution of hydrogen chloride to a solution of the free base in methyl ethyl ketone until the solution is faintly acidic. With the addition of dry ether, the hydrochloride precipitates as a colorless solid which melts at 235-236° C. after recrystallization from methyl ethyl ketone.

The compounds of our invention can be incorporated

into various oral pharmaceutical preparations such as tablets, capsules, elixirs, syrups, nasal sprays, suppositories, and the like, by mixing the same alone, or in conjunction with other active ingredients with various

proportions of pharmaceutical carriers suitable for the preparation being made. Active ingredients which may be used with the compounds of our invention are: aminophylline, prednisone, ephedrine sulfate, potassium iodide, codein sulfate or phosphate, phenobarbital, perphenazine, calcium phosphate, chlorpheniramine maleate, and the like. The recommended optimum dose range for oral administration of the claimed compounds, is from 0.5 to 2 mg. t.i.d.

The compounds of our invention can also be administered intravenously, preferably in the form of aqueous solutions of their non-toxic amine salts (such as the hydrochloride), in the presence of preservatives such as methyl paraben, propyl paraben, and the like. Other active ingredients such as those used in the oral preparations may also be used in these parenteral compositions. From 0.1 to 0.4 mg. of the phenothiazine compound per parenteral dose is the optimum range recommended.

The proportions of active ingredients in our compositions can be varied over a substantial range, subject to the practical limitation that a sufficient proportion of active ingredient be present to provide a suitable dosage. Obviously, the practice of administering several unit dosage forms at about the same time can be followed. The dosage of these compounds may be varied, depending on the requirements of the patient. The following formulations are intended as illustrative only, and are not to be construed as limiting the scope of the invention.

EXAMPLE 7

Table

		Mg.
10-(N-methylisonipecotyl)-phenothiazine hydrochloride	1.00	
Lactose	48.05	
Starch	20.60	
Starch paste	Gs	
Magnesium stearate	0.35	

The 10-(N-methylisonipecotyl)-phenothiazine hydrochloride is mixed with the lactose and the starch. A 10 percent starch paste is prepared and the mixed powders granulated therewith. This wet granulation is passed through a No. 12 screen and then dried at 50° C. for twelve hours, or until the moisture content is less than 0.5 percent. The dry granules are passed through a No. 16 screen, incorporated with the remainder of the starch and magnesium stearate, and then pressed into tablets.

EXAMPLE 8

Table

		Mg.
10-(N-methylisonipecotyl)-phenothiazine hydrochloride	1.00	
Aminophylline	100.00	
Calcium phosphate	30.00	
Lactose	65.62	
Starch	40.98	
Starch paste	Gs	
Magnesium stearate	2.40	

The 10-(N-methylisonipecotyl)-phenothiazine hydrochloride, aminophylline, and calcium phosphate are made into tablets by the procedure described in Example 7.

EXAMPLE 9

Hard gelatin capsule

		Mg.
10-(N-methylisonipecotyl)-phenothiazine hydrochloride	1.00	
Prednisone	5.00	
Lactose	432.00	
Magnesium stearate	2.00	

The 10 - (N - methylisonipecotoyl) - phenothiazine hydrochloride and prednisone are mixed thoroughly with the lactose. Magnesium stearate is then added and mixed until the composition is uniform. No. 1 hard shell capsules are then filled with this uniform mixture.

EXAMPLE 10

Soft gelatin capsule

	Mg.
10-(N-methylisonipecotoyl)-phenothiazine hydrochloride	1.00
Ephedrine sulfate	25.00
Lactose	10.00
Beeswax	2.00
Corn oil	172.00

One milligram of 10-(N-methylisonipecotoyl)-phenothiazine hydrochloride and 25 milligrams of ephedrine sulfate are mixed with the lactose, then passed through a No. 80 mesh screen. This mixture is added to the corn oil and put through a rotor and atator type mill set at a small opening size. The beeswax, which had been melted at 60° C., is poured into this milled suspension with constant stirring. Stirring is continued until there is a homogeneous suspension which is filled into soft gelatin capsules. Seal capsules.

EXAMPLE 11

Elixir

	Quantity/l.
10-(N-methylisonipecotoyl)-phenothiazine hydrochloride	gm. 0.2
Aminophylline, U.S.P. XV	gm. 20.0
Amaranth, U.S.P. XV	gm. 0.1
Syrup, U.S.P. XV	ml. 150.0
Glycerin, U.S.P. XV	gm. 450.0
Orange oil, U.S.P. XV	gm. 2.5
Alcohol, U.S.P. XV	gm. 100.0
Purified water, U.S.P. XV, q.s. 1.01.	

The aminophylline and amaranth are dissolved in approximately 150 ml. of purified water, then the syrup and glycerin are added. The 10-(N-methylisonipecotoyl)-phenothiazine hydrochloride and the orange oil are dissolved in alcohol, and the resultant solution is added to the elixir base. Sufficient purified water is added to make the total volume one liter. The solution is filtered, if necessary, until clear.

EXAMPLE 12

Syrup

	Quantity/l.
10 - (N - methylisonipecotoyl)-phenothiazine hydrochloride	gm. 0.2
Potassium iodide, U.S.P. XV	gm. 13.0
Compound sarsaparilla syrup, N.F. X, 1.01.	

The 10-(N-methylisonipecotoyl)-phenothiazine hydrochloride and potassium iodide are dissolved in a quantity of compound sarsaparilla syrup sufficient to make the total volume measure one liter. The solution is filtered, if necessary, until clear.

EXAMPLE 13

Suppository

	Gm.
10 - (N - methylisonipecotoyl)-phenothiazine hydrochloride	0.1
Aminophylline, U.S.P. XV	30.0
Theobroma oil, U.S.P. XV—A sufficient quantity to make 100 suppositories.	

The ingredients are mixed intimately and prepared according to the process of cold compression to form 100 rectal suppositories, each of which weighs approximately 2 gm.

EXAMPLE 14

Nasal drop and/or spray

	Quantity/l.
10-(N-methylisonipecotoyl)-phenothiazine hydrochloride	gm. 1.0
Chlorpheniramine maleate, U.S.P. XV	gm. 3.0
Sorbitol solution, N.F. X	gm. 70.0
Benzalkonium chloride solution, 12.8%	ml. 1.95
Purified water, q.s. 1.0 l.	

The 10-(N-methylisonipecotoyl)-phenothiazine hydrochloride and chlorpheniramine maleate are dissolved in a suitable quantity of water. The sorbitol and benzalkonium chloride solutions are added, then sufficient purified water to make the total volume of one liter. The solution is filtered until clear.

EXAMPLE 15

Parenteral solution

	Gm./liter
10 - (N - methylisonipecotoyl)-phenothiazine hydrochloride	0.10
Methyl Paraben	1.80
Propyl Paraben	0.20
Water for injection, q.s. ad. 1.00 liter.	

The ingredients are dissolved in the water for injection, filtered, filled into ampules or vials, and sterilized by autoclaving.

EXAMPLE 16

Parenteral solution

	gm./liter
10 - (N - methylisonipecotoyl)-phenothiazine hydrochloride	gm./liter 0.20
Phenobarbital	gm./liter 15.00
Propylene glycol	cc. 900
Methyl Paraben	gm./liter 1.8
Propyl Paraben	gm./liter 0.2
Water for injection, q.s. ad. 1.00 liter.	

The 10-(N-methylisonipecotoyl)-phenothiazine hydrochloride is dissolved in about 50 ml. of water for injection. The other ingredients are dissolved in the propylene glycol. The solutions are mixed, bringing the volume to one liter with water for injection, filtered, filled into ampules or vials, and sterilized by autoclaving.

EXAMPLE 17

Parenteral solution

	Gm./liter
10 - (N - methylisonipecotoyl)-phenothiazine hydrochloride	0.20
1 - (2 - hydroxyethyl) - 4[3 - (2 - chloro - 10-phenothiazinyl)-propyl] piperazine	0.10
Sodium biphosphate	20.0
Sodium phosphate	1.5
Methyl Paraben	1.8
Propyl Paraben	0.2
Water for injection, q.s. ad. 1.00 liter.	

The ingredients are dissolved in the water for injection, filtered, filled into ampules or vials, and sterilized by autoclaving.

We claim:

1. Compounds having the formula:

75 wherein X is a member of the group consisting of hy-

drogen, lower alkanoyl, trifluoromethyl, and a halogen atom having an atomic weight between 30 and 80, and the non-toxic acid addition salts thereof.

2. Phenothiazines having the formula:

3. Phenothiazines having the formula:

4. Phenothiazines having the formula:

wherein Hal. is a halogen having an atomic weight between 30 and 80.

5. Phenothiazines having the formula:

15 wherein X is lower alkanoyl.

6. 10-(N-methylisonipecotoyl)-phenothiazine.

7. 2 - trifluoromethyl - 10 - (N-methylisonipecotoyl)-phenothiazine.

20 8. 2 - acetyl - 10 - (N-methylisonipecotoyl) - phenothiazine.

9. 2 - chloro - 10 - (N-methylisonipecotoyl) - phenothiazine.
